[57] CLAIM

The ornamental design for a container for waste ex-
pelled from a blood gas analyzer or the like, as shown.

DESCRIPTION

FIG. 1 is a perspective view of a container for waste
expelled from a blood gas analyzer or the like, showing
our new design;

FIG. 2 is a side elevational view thereof, the opposite
side elevational view being identical;

FIG. 3 is a front elevational view thereof; and,

FIG. 4 is a bottom plan view thereof.

*Fig. 1.**Fig. 2.**Fig. 3.*

Fig. 4.

UNITED STATES PATENT AND TRADEMARK OFFICE
CERTIFICATE OF CORRECTION

PATENT NO. : Des. 325,257

DATED : April 7, 1992

INVENTOR(S) : J. Anderson, et al

It is certified that error appears in the above-identified patent and that said Letters Patent is hereby corrected as shown below:

On the title page:

In the claim: delete "a container for waste expelled from a blood gas analyzer or the like, " and read --container for liquid--.

Signed and Sealed this
Tenth Day of August, 1993
